UNITED STATES PATENT OFFICE.

GUSTAV R. RODDY, OF MILWAUKEE, WISCONSIN, ASSIGNOR TO CHAIN BELT COMPANY, OF MILWAUKEE, WISCONSIN, A CORPORATION OF WISCONSIN.

LIQUID-SCREENING APPARATUS.

Application filed October 19, 1921, Serial No. 508,846. Renewed May 22, 1926.

My invention relates to sectional traveling screens such as are employed in the treatment of sewage or the waters taken from streams to be used for industrial purposes, and has for its object to improve such apparatus as will be hereinafter pointed out.

In the accompanying drawings—

Figure 1 is a plan view of a section of water screen embodying my invention, parts being broken away.

Fig. 2 is a longitudinal sectional view taken on the line II—II of Fig. 1.

Fig. 3 is a longitudinal sectional view taken on the line III—III of Fig. 1.

Fig. 4 is a perspective view illustrating two links of one of the chains and a portion of one of the screen plates.

The screen herein illustrated consists of a series of perforated metal plates 2 supported at their longitudinal or side edges by chains 3, 3.

In practice the chains 3 are endless, being in fact sprocket conveyor chains, carrying the screen plates 2. As the supporting and driving mechanism for the chains forms no part of the present invention it is not shown in the drawings.

Each chain 3 is made up of a series of connected articulated links, each having an outer side bar 4 and an inner side bar 5. The inner side bar is wider than the outer one, that is, it has greater vertical dimensions, considering the chain as arranged horizontally. These inner side bars of the links are sometimes termed attachment side bars because it is to them, rather than to the outer side bars 4, that the screen plates are secured, either meditately or immediately.

6, 6 indicate cross bars connected with and uniting the inner side bars of corresponding links in the two chains and operating to prevent the screen plates from sagging at their transverse central portions, and also to stiffen and give strength to the conveying elements of the screen. They are preferably of considerable depth to give the necessary rigidity to the structure. There are preferably a pair of these cross bars at each end of each link, and they are spaced apart by the pieces 7. The cross bars are connected, at their ends, with the inner side bars 5 by angle pieces 8. The upper edges of the inner side bars and of the cross bars

are in the same plane so as to afford firm all-round supports for the screen plates. These are secured in place by bolts 9, which preferably pass between the cross bars 6, as represented in Fig. 3.

The screen as thus far described is similar, except for minor details, to that shown and claimed in the pending application for Patent No. 284,926 filed March 25, 1919, by George B. Welser, Jr., which application has matured into Patent 1,435,770 dated November 14, 1922. In operating with such a screen it is found that the load of the chains—the screen plates 3 and the material which they collect—is not evenly divided between the side bars of the chains, but is borne principally by the inner side bars 5, since the screen plates are connected directly therewith. This causes unequal wear at the joints of the chain and the rollers 10 with

which the chains are provided wear more rapidly at one side than the other, so that the life of the chain is reduced. In the screen shown in the aforesaid Welser application for patent the expedient resorted to to prevent this unequal wear of the rollers 10 was by uniting the two side bars of each link by rivets. This added considerably to the expense of the chain and was not in all respects satisfactory. I have

therefore devised the following means for uniting the links of the chain, and for connecting together the opposite chains at their joints, which overcomes the difficulties and objections just suggested, due to the screen plates being directly supported by the inner side bars of the chain links only.

11 indicates a through rod the opposite end portions of which serve as the connecting pins for uniting the links of the two chains 3, 3. The intermediate portions of each rod are bent, at 12, 12, in order that the rod may pass below the cross bar 6, thus permitting the latter to have sufficient depth to give them the desired strength. The through rods 11 connect together the opposite chains and hold them in proper relationship to each other, and at the same time they prevent the chains from twisting, due to the load being unequally divided between the side bars, with the result that the joints of the chains and the rollers 10 wear with great uniformity. These through rods may be straight but this would mean either moving over the cross bars 6 so the through

rods might lie between them, which would reduce the effective screening area, or else the height of the side bars 5 of the chains would have to be increased sufficiently to 5 permit the supporting cross bars 6 to be entirely above the through rods, and this would be undesirable, and therefore the bent rod is the preferred form of construction.

However the through rods may be constructed and arranged it is essential that 10 they be entirely below the screen plates 12 and the transverse bars, angles or other parts that support them.

What I claim is:

15 In a water screening apparatus, the com-

bination of a pair of parallel supporting and conveying chains the links of which have outer and inner side bars, screen plates supported at their side edges by the inner side bars of the opposite chain links, deep, 2 narrow transverse cross bars which serve to support the screen plates at their front and rear edges, and through rods uniting the opposite chains, the rods being bent 2 near their ends so as to pass below the deep transverse cross bars, and the ends of the rods serving as the connecting pins that unite the links of the chains.

GUSTAV R. RODDY.
